CLAIM

The ornamental design for a heads-up display device, as shown and described.

DESCRIPTION

FIG. 1 shows a side perspective view of a heads-up display device of our design;

FIG. 2 shows a front-perspective view thereof;

FIG. 3 shows a top-perspective view thereof;

FIG. 4 shows a rear-perspective view thereof;

FIG. 5 shows a bottom-perspective view thereof;

FIG. 6 shows a side-perspective view thereof;

FIG. 7 shows a side-perspective view thereof; and,

FIG. 8 shows a perpendicular side-view thereof.

The broken lines illustrate portions of the heads-up display device that form no part of the claimed design.
